MATERIAL FEEDING AND CRUSHING APPARATUS

Edward E. Hartford, Toronto, Ohio

Application June 28, 1941, Serial No. 400,172

5 Claims. (Cl. 83—53)

This invention relates to a novel apparatus for continuously feeding materials through an opening, and is designed particularly for continuously feeding tempered clay into a forming or extrusion press.

Another object of equal importance is to provide a novel mechanical apparatus which may be utilized for crushing or pulverizing solid materials, as stone, raw clay, raw shale, coal, or any solid material to be reduced.

My invention may be readily understood by reference to the accompanying drawings which illustrate certain present preferred embodiments of the invention and in which—

Figure 1 is a longitudinal vertical sectional view of the apparatus adapted to feed tempered clay into a forming or extrusion press;

Figure 2 is a transverse vertical sectional view of the same;

Figure 3 is a fragmentary detail sectional view taken substantially on line 3—3, of Fig. 1;

Figure 4 is a side elevational view, partially broken away and with some parts shown in section, of a modified form of the apparatus used for crushing or pulverizing solid materials;

Figure 5 is a detail view of the means for adjusting the breaker plate of the crusher apparatus; and

Figure 6 is a vertical sectional view taken on line 6—6 of Fig. 4.

Referring, first, to Figs. 1, 2 and 3 of said drawings, the reference numeral 1 designates a housing for the apparatus and the numeral 2 designates a hopper for receiving tempered clay in lumps.

Bolted to the end of the housing 1 at opposite sides thereof are bearings 3 in which is journaled a shaft 4 designed to be rotated by any suitable source of power (not shown). A V-belt sheave 5 is fixed to said shaft 4 at opposite sides of the housing and each of said sheaves is connected by V-belts 6 to a corresponding larger sheave 7 keyed to a shaft 8 at opposite sides of the housing to provide a tandem drive. While V-belts are herein shown and described for actuating the apparatus, it will be understood that flat belts; link chains; sprockets or the like may be utilized for this purpose.

Keyed to the shaft 8 and disposed interiorly of the housing beneath the hopper 2 is the hub 9 of a hollow drum 10. The drum shown in the drawings has a pentagonal shape in transverse section, but it will be understood that, while this shape may be preferred, the shape may also be

that of any regular polygon having an unequal number of sides.

The shaft 8 is journaled in oppositely disposed bearings 12 provided with webs 13 on their upper and lower surfaces. Said webs are adapted to be slidably received in spaced, parallel, longitudinally disposed gibs 14 which are bolted to the housing. Obviously, therefore, said shaft 8 and all the elements carried thereby are free to move longitudinally in the housing, such movement being permitted by slots 15 in the housing side walls, as shown in Fig. 3.

Extending transversely interiorly of the housing is a fixed axle 16 on which a roller 17 freely rotates, the rotation being facilitated by roller bearings 18 interposed intermediate the shaft and the roller.

The belts 6 are maintained taut by weighted idler pulleys 19 borne by swinging arms 20 pivotally attached to a shaft 21 borne by the housing. The weight of the swinging arms 20 and pulleys 19 exert a pressure on the upper lengths of the belts so that the belts are taut at all times and the perimeter of the drum 10 is constantly in contact with the roller 17 because of the drag or pull on the lower lengths of the belts 6, together with the weight exerted by the idler pulleys and swinging arms.

In practice, chunks of tempered clay in lump form are placed in the hopper 2 and the apparatus is actuated so that the belts travel in the direction indicated by the arrow in Figure 1 to rotate the drum clockwise. As the drum is so rotated, a quantity of the clay in the lower portion 35 of the hopper contacts one of the flat faces of the drum 10 and is forced forward in the direction of the drum's rotation toward the passage 22 leading to the press. As rotation continues, the perimeter of the drum is constantly riding 40 on the roller 17 toward the vertex of the angle diametrically opposite the drum face approaching the passage 22 so that, when said vertex is contacted by the roller 17, the diametrically opposite flat face of the drum and the quantity of the clay engaged thereby are forced toward the opening thereby forcing the clay through a screen grid 23 into the passage 22 leading to the press, the grid 23 serving to prevent clay already in the opening from being forced backward from the passage into the feeding apparatus. During the period that the clay is engaged by the face of the drum and is being moved toward the passage, it is manifestly being subjected to a squeezing action so that a substantial portion of the inherent air is squeezed and extracted

from the clay. Thus, the clay is delivered to the press in a substantially compacted state.

As one face of the drum produces the squeezing action to transport and force clay to and through the passage 22, the next face following is commencing to produce the same action and result and each succeeding face will do likewise as it reaches a similar station in the drum's rotation.

It will, of course, be understood that, during operation of the apparatus, the shaft 8 and the elements borne thereby are continuously reciprocated backward and forward, being permitted to do so by reason of the shaft bearings 12 being slidable in the gibs 14. Any slack in the belts 6 is taken up by the idlers 19 and swinging arms 29 so that the belts are taut at all times.

As shown in the drawings, the plate faces of the drum 10 are individually removable for purposes of replacement and repair.

Referring, now, to Figs. 4, 5 and 6, illustrating the crushing apparatus, the reference numeral 1^a designates a housing for the apparatus and the numeral 2^a designates a hopper for receiving the solid material to be acted upon.

Power from a suitable source (not shown) drives a shaft 25 on the opposite ends of which a driving pinion 26 is keyed. Each pinion 26 meshes with a gear 27 keyed to the shaft 8^a on which the drum 10^a is mounted. The shaft 8^a is journaled in bearings 28 provided in the upper ends of oppositely disposed swinging arms 29 which are free to oscillate about the drive shaft 25. The polygonal perimeter of the drum 10^a is maintained in constant contact with the roller 17^a by spiral compression springs 30 interposed between a boss formed on each swinging arm 29 and a spring support 31 attached to the housing.

A breaker plate 32 is carried interiorly of the housing in alignment with the forward face of the drum 10^a. Said breaker plate 32 is adapted to be moved toward and away from the drum 10^a so as to regulate the size of the solids acted upon. This adjustment is provided for by means of a tapered wedge 33 interposed between the rear surface of the plate 32 and an inclined strengthened portion of the housing 1^a. The adjustment is made by temporarily loosening the retaining bolts 34 and then manually rotating the adjusting screw 35, the upper end of which is freely rotatable in a boss 36 extending from the housing and the lower threaded end of which is received by threads provided in a lug 37 formed on the wedge 33 and which protrudes exteriorly of the housing through a slot 38. Obviously, lowering of the wedge will force the breaker plate inwardly toward the drum to decrease the space therebetween for crushing finer solids and vice versa.

Stationary brackets 39 fixed to the housing afford permanent support for the breaker plate and assures that the plate will be maintained in proper vertical position while adjustment is being made.

The purpose of the above described apparatus, as hereinbefore pointed out, is to crush or pulverize solid materials, as stone, raw clay, raw shale, coal, and the like, in a continuous manner by the simultaneous rotation and oscillation of

the drum 10^a, the material gravitating from the hopper 2^a on to the drum from whence it is conveyed by rotation of the drum to the space between a face of the drum and the breaker plate where it is crushed or ground and is thereafter free to gravitate through the open bottom of the housing into an appropriate receptacle.

An opening 40 is provided in the housing to permit oscillation of the shaft 8^a, said opening being of a size which will permit of access to the interior for making repairs, etc.

What is claimed is:

1. An apparatus for applying pressure to materials including a vertically disposed member, a rotatable drum of polygonal cross-section having an unequal number of faces, means to supply material to said faces of the drum, means to rotate the drum whereby to cause same to successively present its faces to the member thereby to exert pressure on the material between a face of the drum and the member, means to mount the drum for bodily longitudinal movements to and from said member, means fixed at a point stationary with respect to the drum, and acting 20 against the perimeter thereof at a point diametrically opposite to the member to maintain the faces of the drum in predetermined relation to the member, and means normally urging the drum into contact with said drum engaging means.

2. An apparatus in accordance with claim 1, wherein the drum maintaining means includes a rotatable backing roller.

3. An apparatus for applying pressure to materials including a vertically disposed member, a rotary drum of polygonal cross-section having an unequal number of similar angularly related faces, means to supply material to the faces of said drum, means to rotate the drum whereby to cause same to successively present its faces to the member whereby to exert pressure on the material between a face of the drum and the member, means to mount the drum for bodily longitudinal movements to and from said member, a backing roller having its axis of rotation fixed at points stationary with respect to the drum and acting against the perimeter thereof at a point diametrically opposite to the member to maintain the faces of the drum in predetermined relation to the member, and spring actuated means to hold the perimeter of the drum in constant engagement with the roller.

4. An apparatus for applying pressure to material in accordance with claim 1 wherein the member has a substantially plane material engaging face substantially equal in area to the faces of the drum.

5. An apparatus of the type set forth including a material-engaging member, a drum of polygonal cross-section mounted for bodily longitudinal movements and having an unequal number of sides cooperable with the member to squeeze material between the member and drum sides, means to rotate the drum, backing means for the drum, acting against the perimeter thereof, and means for constantly maintaining contact of the drum periphery and the backing means during rotation of the drum.

EDWARD E. HARTFORD.
